DRILLING HEAD

Herbert C. Otis, Dallas, Tex.

Application September 2, 1937, Serial No. 162,184

10 Claims. (Cl. 255—1)

This invention relates to new and useful improvements in drilling heads.

One object of the invention is to provide an improved drilling head which is particularly adapted for use in packing off around a drill stem of a well, or other progressive element, and which will effectively hold its seal under various conditions, whereby various well operations, such as drilling under pressure, may be performed.

10 An important object of the invention is to provide an improved drilling head having an elastic packing member through which the rotatable drill stem or kelly extends, together with pressure means for distorting said member into packing position around the stem or kelly; the head being so constructed that it may undergo a limited swinging or tilting movement without breaking its packing seal with the stem, whereby the head is self-aligning to compensate for irregularities in the stem or kelly, misalignment of the well connections with the drive member through which the stem or kelly extends, or lateral movement of said drive member.

15 A further object of the invention is to provide an improved drilling head of the character described, having pressure means for distorting the packing member, and being so constructed that the pressure fluid may be utilized to lubricate the bearing members of the head, said means also being so constructed that it does not interfere in any way with the swinging or tilting of the head.

20 Still another object of the invention is to provide an improved drilling head including an outer member having an inner member rotatable therein, with improved bearing elements between the members so as to permit the inner member to undergo lateral movement, as well as to swing or tilt within the outer member; said inner member having a deformable packing therein for engaging the drill stem or kelly to pack off therearound and being arranged to be deformed into packing position by fluid pressure.

25 A construction designed to carry out the invention will be hereinafter described, together with other features of the invention.

The invention will be more readily understood from a reading of the following specification and by reference to the accompanying drawings, in which an example of the invention is shown, and wherein:

30 Figure 1 is a view, partly in elevation and partly in section, of a drilling head, constructed in accordance with the invention,

Figure 2 is a horizontal, cross-sectional view, taken on the line 2—2 of Figure 1.

Figure 3 is a view similar to Figure 2 with the packing element in its distorted position.

Figure 4 is a view, similar to Figure 1 of a modified form of the invention, and

Figure 5 is a reduced view, partly in elevation and partly in section, of a modified form of the upper portion of the drilling head.

35 In the drawings, the numeral 10 designates a cylindrical casing or shell which has its lower end bevelled at 11, whereby the shell may be mounted within a suitable housing or support 12. The housing is provided with an internal annular seat 13 on which the bevelled lower end 11 of the shell is supported. A suitable retractile latch member 14 which is mounted in the upper end of the housing 12, is adapted to overlie an external shoulder 15 which is formed near the lower end of the shell 10. Manifestly, the latch member 14 serves to prevent upward displacement of the shell from the housing 12, and it is pointed out that said latch forms no part of the present invention, being described merely for the sake of clarity. The shell has a vertical bore 16 which has its lower end reduced in diameter at 17, and between said bore and this reduced portion, an internal annular flange 18 is formed. A second inwardly directed annular flange 19 is located at substantially mid-height of the reduced portion 17 of the bore, while an internal annular shoulder 20 is provided at the extreme lower end of said reduced portion.

40 Rotatably mounted within the shell 10 is an elongated cylindrical body 21 which has substantially the same length as the shell. The diameter of the body is less than the inner diameter of the internal flanges 18 and 19, whereby the body may move a limited distance laterally within the shell. An upwardly directed annular flange 22 is spaced from the bore 23 of the body 21 and is located near the lower end of said bore. The flange 22 is preferably made integral with the body 21 and manifestly the disposition of said flange forms an annular recess 24 within the bore of the body. This recess is adapted to receive the lower reduced end of a packing sleeve or element 25. The packing element normally has its outer surface engaging the wall of the bore 23. The upper end of said packing element is reduced and this reduced portion is engaged by a flanged ring or collar 26 which is inserted within the bore of the body 21. A packing gland nut 27 is screw-threaded into the upper end of the body 21 and has its lower end engaging the

top of the ring or collar 26 to hold the same within the body.

If desired, a suitable packing ring 28 may be interposed between the ring or collar 26 and the wall of the bore 23, as is clearly shown in Figure 1, to prevent leakage upwardly therebetween. However, it may be preferable to omit the packing ring 28, and to provide annular sealing lips 25' on the outer surface of the packing element 25. The lips are located near the upper and lower ends of the element and are so disposed that a pressure fluid, within the bore 23 of the body and between the wall of said bore and the packing element 25, will be trapped between said lips and will act to hold said lips in sealing engagement with the wall of the bore 23, whereby leakage in either an upward or downward direction will be prevented.

From the above, it will be seen that the packing element 25, which is preferably constructed of rubber, rubber compound, or other elastic material, is confined within the bore of the body 21 between the recess 24 and the retaining ring or collar 26. By removing the gland nut 27 from the upper end of the body 21, the collar or ring 26 and the packing element 25 may be readily removed from the bore and a new packing element may be inserted within said bore. As is clearly shown in Figure 2, the elastic packing element or sleeve 25 is provided with a plurality of vertical grooves or recesses 29, which recesses are formed in the inner face of said element. The recesses terminate short of the upper and lower ends of the packing element, extending only throughout the central portion of said element. Similar grooves or recesses 30 are formed in the outer face of the packing element and these latter grooves are staggered with relation to the grooves 29. It will be evident that the grooves 30 are located adjacent the wall of the bore 23 of the body, while the grooves 29 are located adjacent the exterior surface of the drill stem which extends through the device. The provision of the vertical grooves in the packing element permits said element to be deformed to the position shown in Figure 3, which reduces the diameter of the element, while maintaining a smooth inner surface for engagement with the drill stem or kelly.

For rotatably supporting the body 21 within the shell 10, said body is formed with an external annular flange 31 which is located substantially at the mid-height thereof. The flange extends into the bore of the shell and is of such width that when the body is disposed axially within said shell, there is a clearance or space 32 between the outer edge of the flange and the wall of the bore 16. As clearly shown in Figure 1, the flange 31 overhangs the internal flange 18 within the shell, which latter flange is provided with an annular recess or groove 33 in its upper face. This groove receives an elastic supporting ring 34 which has its upper end projecting from the groove. A metallic antifriction ring 35, preferably of bronze, is supported on the elastic ring and surrounds the body 21. It is noted that the outer edge of the ring is contiguous to the wall of the bore 16 of the shell, there being a slight clearance therebetween, while there is a comparatively large clearance between the inner edge of said ring and the body 21.

The external flange 31 on the body rests on the antifriction ring 35 whereby the body is suspended from the flange and due to the clearance between the flange and the bore 16 as well as

the clearance between the inner edge of the ring 35 and the body 21, said body may move a limited lateral distance within the shell. To permit free rotation of the body within the shell, ball bearings 36 are mounted in annular races 37 which are supported on the flange 31. The outer edges of the races do not contact the bore 16 of the shell 10, leaving a clearance space which allows the races to move laterally with the body. The upper face of the upper race is arcuate as shown at 38 and is engaged by the arcuate underside of a retaining ring or follower 39. The ring 39 is held within the shell by a nut 40 which is screwed into the upper end of the shell 10. As clearly shown in Figure 1, the bore of the nut 40 is recessed at 41 to receive a plurality of V-shaped packing rings 42 which pack off the space between the nut and the body 21. The shape of the packing rings 42 is such that a pressure from within the shell 10, that is, a pressure from within the annular space between the shell 10 and the body 21 will cause a distortion of the packing rings to force them into close sealing engagement with the exterior surface of the body 21.

For packing off the space between the reduced portion 17 of the bore of the shell 10 and the exterior surface of the body 21, a plurality of resilient packing rings 43, similar to the rings 42, are supported on the flange 19, which extends inwardly from the reduced portion of the bore of said shell. These rings are so disposed that a pressure from within the annular space between the body 21 and the shell 10, expands the same into sealing engagement with said shell and body 21. To prevent the well pressure from escaping upwardly between the body 21 and the shell 10, a plurality of packing rings 44, which are of an inverted V-shape, are located between the extreme lower end of the body 21 and the bore of the shell 10. As is clearly shown in Figure 1, the rings 44 are positioned directly beneath the flange 19.

In operation, the drill stem or kelly A extends through the device, that is, through the body 21. In the drawings, a kelly is shown and the normal position of the packing element 25 is such that there is a clearance between the bore of said element and the exterior surface of the kelly. In order to obtain a seal between the body 21 and the kelly A, it is necessary that the packing element 25 be moved inwardly into snug engagement with the exterior surface of said kelly. When this is done, the well pressure cannot escape through the space between the kelly and the body 21. As before pointed out, said well pressure cannot by-pass through the space between the body 21 and the shell 10 because of the lowermost packing rings 44, which are forced into sealing engagement by said pressure. The well pressure is, therefore, completely sealed off and held.

For distorting the packing element 25 so as to move the same into engagement with the exterior surface of the kelly A extending therethrough, the flange 31 on the body 21 is provided with a plurality of radial ports 45 which extend entirely through the flange and communicate with the interior of the body 21. A pressure fluid line 46 is connected in a radial opening 47 provided in the wall of the shell 10 and serves to supply a pressure fluid to the interior of the shell 10.

When it is desired to contract or deform the packing element 25 into its sealing position, pressure fluid is introduced through the line 46 into the space between the shell 10 and the body 21.
